ARTIFICIAL FOOT

Filed March 23, 1929

INVENTOR

EARNEST R. LEAF.
By C. J. Blake Atty.

UNITED STATES PATENT OFFICE

EARNEST R. LEAF, OF PORTLAND, OREGON

ARTIFICIAL FOOT

Application filed March 23, 1929. Serial No. 349,354.

My invention relates to artificial feet, the object being to provide improved means for securing the yieldable sole to the body of the foot; a further object being to provide 5 against the breaking down of the yieldable sole at the point whereat it naturally bends over the forward end of the body when in use. I accomplish these objects by means of the construction illustrated in the accompanying drawings, which is a part of this 10 application for Letters Patent, like characters of reference indicating like parts throughout the several views thereof, and in which:

15 Fig. 1 is a longitudinal sectional elevation of an artificial foot embodying my invention.

Fig. 2 is a sectional elevation upon the line 2—2 of Fig. 1.

20 The body of the foot 3 may be constructed of any suitable material, preferably wood, and is shaped in simulation of a human foot. The yieldable sole is composed of alternate layers of yieldable material such as sponge rubber or the like 4, with woven fabric 5 between each layer of the said yieldable material. The fabric may be either moulded into the yieldable material to form an integral whole for the sole, or it may preferably be cemented to the yieldable material.

25 30 It has been found difficult in the art to securely cement or secure the yieldable sole upon the body portion 3 of the foot. I have discovered that a yieldable sole composed of rubber can be more securely cemented to leather than it can be to wood, and also that leather can be satisfactorily secured to wood. Therefore I provide a strip of sole-leather 6 disposed intermediate the yieldable sole and the body of the foot, and cemented to each.

40 45 To provide that the leather joint between the yieldable sole and the body of the foot may be watertight I provide a thin raw hide covering 7 for the lower portion of the foot body, which raw-hide covering is extended downward just over the edge of the sole-leather strip 6, as shown in Fig. 2. This covering is cemented in place, and thus seals the joint between the leather strip and the body upon one side thereof and the yieldable sole upon the other side thereof.

It has been found difficult in the art to prevent the yieldable sole from breaking down at the forward end of the foot body, and to overcome that I have provided a member composed of felt 8 disposed upon the leather strip 6 and contacting with the foot body 3 some distance rearward of the toe of the foot, and upon a plane downwardly and rearwardly inclined as shown at 9 in Fig. 1.

45 50 The entire foot is then covered with a covering 10 of leather cemented in place.

The result of this construction is two fold. First it provides a satisfactory means of securing the yieldable sole upon the foot body; second it provides a rounded corner at the 55 front portion of the foot about which the yieldable sole may bend, protected at said point also by the leather strip 6.

55 60 My invention may be made of any materials deemed convenient and suitable for a device of this character, and made of any size desired and while I have illustrated and described a form of construction found desirable in materializing my invention I wish to include in this application all mechanical equivalents and substitutes that may fairly be considered to come within the scope and purview of my invention as defined in the appended claims.

65 70 Having disclosed my invention so that others may be enabled to construct and to use the same, what I claim as new, and desire to secure by Letters Patent is:

75 80 1. In an artificial foot: a yieldable sole; a body above said sole; a fibrous cushion member above said sole at the toe of said foot; a leather strip intermediate said sole and said parts thereabove, said leather strip being cemented to said parts adjacent thereto upon each side thereof; and a raw hide covering for said body and said cushion, said covering extending over the edge of said leather strip to protect the cemented joints thereof with the parts immediately adjacent thereto upon either side.

85 90 95 100 2. In an artificial foot: a body portion; a fibrous cushion member at the toe of said foot; a leather strip upon the bottom of said body portion and extending therefrom beneath said cushion member, and cemented to

each; and a covering for said body portion and said cushion member, said covering extending over the edge of said leather strip to protect the cemented joints between said strip and the portions immediately adjacent thereto.

3. In an artificial foot: a yieldable sole; a rigid body above said sole; a cushion above said sole forward of said body; a strip of flexible material intermediate said sole and the said portions thereabove; and a moisture impervious covering for the edges of said strip of flexible material.

In witness whereof I claim the foregoing as my own I hereunto affix my signature at Portland, county of Multnomah, State of Oregon, this 18th day of March, 1929.
